UNITED STATES PATENT OFFICE.

GERHARD MATHIS, OF NEW YORK, N. Y.

CLOTHES-LINE FASTENER.

SPECIFICATION forming part of Letters Patent No. 779,172, dated January 3, 1905.

Application filed August 17, 1904. Serial No. 221,060.

To all whom it may concern:

Be it known that I, GERHARD MATHIS, a citizen of the United States, residing at New York city, (Brooklyn,) county of Kings, and State of New York, have invented new and useful 5 Improvements in Clothes-Line Fasteners, of which the following is a specification.

This invention relates to a clothes-line fastener which is of simple construction and permits the tension of the line to be easily and accurately regulated.

In the accompanying drawings, Figure 1 is a side view of my improved clothes-line fastener. Fig. 2 is a longitudinal section thereof, 15 showing it closed; Fig. 3, a similar section showing it partly open, and Fig. 4 a plan.

In carrying out the invention I employ a frame a , which is made of a single piece of metal. This frame has an eye a^2 near one end 20 of its shank portion and a longitudinal slot a' , that is closed at both ends to provide an inner gripping or clamping surface a^3 on its broadened jaw portion a^4 . The inner face of the jaw a^4 is bulged near the top to provide a nose a^5 , which merges into a lower reentrant or deflected portion a^6 , that curves inwardly. Thus the nose a^5 and deflected portion a^6 form 25 an ogee curve, which establishes a sinuous gripping-surface for the line, as shown in Fig. 30 2. This gripping-surface is provided with a longitudinal groove of uniform depth, which forms a sinuous recess or socket for the line. b designates a lever pivoted in the slot a' at b' , and having an eye b^2 near its outer upper end. 35 The inner lower end of the lever extends into juxtaposition with the gripping-surface a^3 and of the jaw a^4 and constitutes the other jaw of the fastener. The outer face of the jaw b^3 is curved convexedly and grooved longitudinally 40 coincident with the groove in the jaw a^4 , so as to form a longitudinal channel for the line, and thereby present an increased gripping-surface for the periphery of the latter. The convexity

of the gripping-surface b^3 corresponds to the concavity of the reentrant portion a^6 of the 45 jaw a^4 and forces the line up into such portion, so that a sinuous channel for the line is established. The gripping action is augmented by forming transverse corrugations on the gripping-face b^3 of the lever.

In practice one end, A , of the clothes-line is passed through eye b^2 of the lever b and knotted, as at A' , and is supported by a pulley in the usual manner. Near the other end the line is passed downward through slot a' 55 of the frame and between the jaws a^4 and b^3 , as at A^2 . The tension on the end A of the line will pull the upper end of the lever b and throw the jaw b^3 upwardly, which will force the portion A^2 of the line into the reentrant portion 60 a^6 of the jaw a^4 , thereby holding the portion A^2 in the sinuous channel formed by the grooves in the jaws. The end A^3 of the line is then passed upward through the eye a^2 and knotted, as at A^4 . By pulling the section A^3 65 of the line the slack may be taken up. To release or slacken the line, the end A^3 is pulled, which raises the jaw a^4 of the frame and releases the grip of the jaw b^3 , as shown in Fig. 3.

What I claim is—

In a clothes-line fastener, the combination of a slotted frame having an eye at one end and a jaw at its other end, the inner face of the jaw having a sinuous groove, and a lever pivoted in the slot and having a curved jaw 75 which is provided with a groove coincident with the said sinuous groove, whereby a sinuous channel for the line is formed, substantially as specified.

Signed by me at New York city, (Manhattan,) New York, this 16th day of August, 1904.

GERHARD MATHIS.
